DOORLATCH

Oscar C. Schmidt, Cincinnati, Ohio, assignor to
 The Cincinnati Butchers' Supply Company,
 Cincinnati, Ohio, a corporation of Ohio

Application October 7, 1933, Serial No. 692,688

1 Claim. (Cl. 292—78)

My invention relates to door latches, especially to latches for doors which it is desired to open and close frequently. My invention is also designed for use with heavy doors, for instance, 5 large refrigerator doors used in butcher shops, packing plants and the like.

It is the object of my invention to provide a simple door latch which is operated by the movement of the door in opening and in closing the door; further, to provide novel latching means whereby the latching lever is tripped by the closing movement of the door for exerting closing force upon the door; further, for providing opening force upon the door when opening the door; 15 further, to provide novel latching means whereby the latching lever may be placed on the wall of the door opening or on the door; further, to provide novel means for operating the latching lever; and, further, to provide novel means in 20 connection therewith for initially urging the door in opening direction.

My invention consists in novel means for accomplishing the objects stated, and in the novel parts and the novel arrangements and combinations of parts hereinafter more fully described and claimed.

The invention will be further readily understood from the following description and claims, and from the drawings, in which latter:

30 Fig. 1 is a front elevation of my improved device, with the door and wall of a refrigerator partly broken away.

Fig. 2 is a plan view of the same, the door and wall being shown in section on the line 2—2 of 35 Fig. 1 and partly broken away.

Fig. 3 is an enlarged vertical section of the latch, taken on the line 3—3 of Fig. 1, and showing the parts in latched relation in full lines, and in unlatched relation in dotted lines.

40 Fig. 4 is a cross-section of the same, taken in the plane of the irregular line 4—4 of Fig. 3.

Fig. 5 is a cross-sectional detail view taken on the line 5—5 of Fig. 1.

45 Fig. 6 is a front elevation showing a modification of my improved device for use with an extra heavy or large door.

Fig. 7 is a horizontal cross-section of the same, taken on the line 7—7 of Fig. 6, and partly broken away.

50 Fig. 8 is a front elevation showing a further modification of my invention showing the latch lever provided with a handle for operating the door.

55 Fig. 9 is a plan view of the same, with the door

and wall in section on the line 9—9 of Fig. 8, and partly broken away.

Fig. 10 is a longitudinal section of the same taken on the line 10—10 of Fig. 8, showing the latch lever in closed relation in full lines, and in open relation in dotted lines.

Fig. 11 is a front elevation of a further modification of my invention, partly broken away, and showing the latch mounted on the door.

Fig. 12 is a plan view of the same, with the 10 door and wall in section on the line 12—12 of Fig. 11, and partly broken away.

Fig. 13 is a side elevation of a still further modification of my improved device, showing the 15 latching means located at the inside of the door.

Fig. 14 is a plan view of the same, with the door and wall in section on the line 14—14 of Fig. 13, and partly broken away; and,

Fig. 15 is a longitudinal section of the same, taken on the line 15—15 of Fig. 13, and showing 20 the latch in latched relation in full lines, and in unlatched relation in dotted lines.

The body 1 of the refrigerator has a door opening 2, arranged to be closed by a door 3 mounted 25 on hinges 4. A sealing cushion 5 is located between a flange 6 which surrounds the door and the outer margin of the door opening, and a sealing cushion 7 is located between the inner margin of the door and a sealing strip 8 secured to the door jamb 9 at the inner end of the door opening. 30 The sealing cushions and sealing strip extend around the door opening.

A latch lever 11 is pivoted on a pivot pin 12, mounted in bearings 13 in side flanges 14 extending from a base 15 which forms a casing 16, the 35 side flanges having a slot 17 therebetween in which the latch lever moves. The casing has a cavity 18, shown formed by the side flanges 14, a cross wall 19 and an end wall 20, forming an 40 enclosing wall of the casing. The base is provided with fastening flanges 21, suitable screws 22 securing the casing in place.

The latch lever is provided with opposed contact faces 26, 27, shown located on wings 28, 29. These contact faces slant obtusely with relation to each 45 other at the respective sides of the pivot of the latch lever and coact with a keeper 31.

The keeper is shown as a pin located in a bearing 32 of a plate 33 secured in place by screws 34. A set screw 35 threaded in the bearing clamps 50 the pin securely in place. The outer end of the pin may be provided with a roller 36 which coacts with the contact faces. A handle 38 extends from the plate 33 for movement of the door.

55 The casing is in Figs. 1 to 10 inclusive shown

secured to the door jamb or wall of the door opening, and the keeper is shown secured to the door.

Referring to Figs. 1 to 5 inclusive, the latch lever has a tail 41. A rod 42 has articulation with the tail, being hinged thereto by a pin 43, located in a bearing hole 44 in said tail and in bearing holes 45 of a fork end 46 of said rod. The outer end of the rod is received in a recess 47 in the end wall 20 of the casing. The inner end of the rod has an enlarged threaded portion 48, over which a nut 49 is threaded.

A helical spring 51 is located about the rod between said nut and the wall 52 of the recess 47. The spring is centered about the rod by the enlarged threaded portion at one end thereof, and an enlargement 53 of said rod at the other end thereof. The outer end of the rod is maintained in said recess for locating said outer end laterally, the outer end of the rod being, however, normally distanced from the bottom of the recess for permitting endwise movement of said rod. Swivel or pivot connection 50 between the outer end of the rod and the end wall of the casing is thus formed.

When the axis of the pivot 43 is located coincident with a right line between the axis of the pivot 42 and the pivotal axis at the outer end of the rod, which right line is represented by the dot and dash line 54, then the latch lever is in dead center position. If the axis of the pivot 43 is moved to either side of said right line, then the spring and rod connection with the tail of the latch lever urge swinging movement of the latch lever to extreme extent, for coaction of either contact face 26, 27 with the keeper, depending on which side of said right line the axis of the pivot 43 is located, for either urging closing movement of the door when the keeper and the contact face 26 are in coaction, or opening movement of the door when the keeper and the contact face 27 are in coaction.

Movement of the latch lever in each direction is limited to place the contact faces in proper positions. Thus the inner one of the wings of the lever is arranged to strike the base at the lug 55 when the latch lever moves in one direction, and the inner corner 56 of the tail of the lever is arranged to strike the base when the latch lever is moved in the opposite direction. The latch lever is provided with a projection 57 having a rounded edge to continuously close the outer end of the slot 17 during various positions of the latch lever.

When the door is in closed relation, the inner wing is distanced from the base by a space 58, so that there is continuous urge of the contact face 26 against the keeper for urging the door into closed relation with continuous pressure so as to thoroughly seal the door.

The pin 31 is preferably polygonal in cross-section, and the bearing 32 therefor is of similar cross-sectional form, and the roller 36 is preferably eccentrically placed with relation to the axis of the pin, as on an eccentric shank 61 of the pin. This permits the pin to be placed in various positions rotatively in the bearings for adjusting the position of the contact roller, and therefore adjusts the closed relation of the door. Placing the eccentric roller at different positions about the axis of the pin places the contact roller at different distances from the planes in which the sealing faces of the door are located, and in different positions with relation to the contact faces

on the latch lever, for obtaining different closing effects upon the door.

It will be noted from the full-line position of the latch lever in Fig. 3, that when the door is in closed relation, the contact face 26 extends upwardly and slantingly outward, with the tail of the latch lever and the rod and spring thereabout tipped outwardly from the right line between the pivot 42 and the pivot 50 at the bottom of the rod 42, the spring exerting inward pressure upon the door, with the inner wing of the latch lever spaced from the base by the space 58. In this relation the contact face 27 and the wing 29 on which it is located, extend substantially horizontally inward and below the path or plane in which the keeper 31 moves when the door is swung.

If now the door be swung to open the door, by pulling upon the handle 38, or pushing upon the door from the inside of the refrigerator, the keeper 31 will move outwardly in a horizontal plane acting in said horizontal plane against the contact face 26, for swinging the latch lever on its pivot in the opposite direction, causing shifting of the pivot 43 and moving it past the right line 54, whereupon the spring and rod connection with the tail of said lever causes swinging of the latch lever for moving the contact face 27 into contact with the keeper, represented by the dotted position of the latch lever in Fig. 3, in which relation outward urge of the contact face 27 is caused upon the keeper for urging the keeper and the door outwardly and aiding in the opening movement of the door.

This movement continues until the stop 56 on the keeper strikes the rear wall of the casing, or the front edge 62 of the latch lever strikes the front end wall 63 of the slot 17, or both these striking movements take place, in which position the contact face 26 and the wing 28 of the latch lever will have moved out of range of the path of the keeper to a position below the level or path of movement of the keeper, so that the door and keeper may be swung outwardly, and placing the lever in such position that when the door is swung into closing relation, the keeper will strike the contact face 27 of the latch lever.

The impact of the keeper upon said latch lever or the moving of the door into closing relation causes tilting of the latch lever so as to again reversely move its pivot 43 to the other side of the right line 54, whereupon the spring and rod connection with the latch lever will cause swinging of the latch lever for closing relation of the door and movement of the contact face 26 against the keeper 31, with the spring urging closing movement of the door.

The door may be opened or closed by merely pulling or pushing on the door from either the inside or from the outside of the door, manipulation of other latching means being unnecessary.

The latch lever is provided with a hole 59 in which the bow of a padlock may be placed for locking the latch lever in closed position, the bow being obstructed by the proximate walls of the casing for preventing pivotal movement of the latch lever.

The inside face of the door may be provided with a handle 64 on a plate 65 secured to the door.

It will be noted that the contact faces 26, 27 have a shallow hollow 66 therebetween. The middle portion of this hollow is in the plane of the right line 54 when the latch lever is in dead center position. The opposed wings and the contact faces 26, 27 thereon extend in opposite directions with relation to each other at the oppo-

site sides of this hollow, so that little movement of either wing or contact face in either direction about the axis of the latch lever is required for permitting traversing movement between the keeper and either of said contact faces with little vertical distance between them while the latch lever is in either of its extreme positions, with the other of said contact faces and wings urged against the keeper by the spring for urging either opening movement or closing movement of the door.

The contact faces 26, 27 extend at substantially obtuse angles with relation to each other at the respective sides of the hollow at the contact end 15 of said latch lever, and when said latch lever is in dead center position the dead center line 54 practically forms a bisector of said obtuse angle, with the bisector substantially coincident with a right line in which the pivots 12, 43 and 50 are located when the latch lever is in dead center position.

Figs. 6 and 7 exemplify a modification of my invention for use especially with large doors or warped doors for insuring closure throughout the 25 margin of the door. In these figures similar parts are designated by similar reference numerals raised to the series 100. The handles on the keeper supports may be dispensed with in this exemplification, and a keeper 131 may be mounted in a bearing 132 of a keeper plate 133 secured at each of the swinging corners of the door. A latch structure is mounted on the door frame or jamb at each of corresponding corners of the door.

35 A handle 138 is mounted on the middle portion of the door, and is shown as part of a lever 168 mounted on a pivot 169 of an escutcheon plate 170 secured to the door. The lever has a load end 171, having a contact face arranged to be pressed upon a contact face of a contact lug 172 secured by screws 173 to the frame or jamb of the door.

A handle 175 is secured to a rod 176, which slides endwise in bearings 177 in the door, and has an outer end which has articulating connection 178 with the handle lever, shown formed by a slot 179 in the handle lever and a pin 180 on the rod received in the slot.

An operator at the outside of the door may 50 open the door by manipulation of the handle 138, and an operator at the inside of the door may open the door by operation of the handle 175. The door may be closed or opened by pulling or pushing respectively upon either handle from the 55 outside or inside of the door.

The latches at the respective corners of the door operate simultaneously automatically by the pushing and pulling movements upon the door in manner similar to the operation of the single latch described in connection with Figs. 1 to 5 inclusive. Separate adjustment of the keepers aid in compensating for different pressures or extents of movements upon the respective corners of the door in case the door should be warped or its closing be uneven at different parts of the door. Latches and keepers may be placed on different parts of the door according to the requirements for closing the door throughout its margin.

70 Referring to Figs. 8, 9 and 10, similar parts are designated by similar reference numerals raised to the series 200. In this modification the latch lever is provided with a handle 283 which extends from the latch lever through the slot 217 and alongside of the front of the casing 216 but spaced

therefrom by a space 284, permitting room by which the handle may be grasped by the hand of the operator for swinging the latch lever by outward swinging of the handle for more intimate sealing of the door, or for initially opening 5 the door by swinging the handle inwardly.

This modification is especially useful where extra heavy doors are employed or where doors fit tightly or with a tendency to bind in the door jamb, the handle on the latch lever being effective to insure intimate closing of the door and ready initial opening movement of the door.

I have in Figs. 11 and 12 shown an additional modification in which the latch lever is mounted on the door and the keeper on the jamb. In these 15 figures similar parts are designated by similar reference numerals raised to the series 300. The latch lever and its mounting are similar to that shown in Figs. 8, 9 and 10. The latch casing is mounted horizontally on the door, and the keeper is mounted vertically on the jamb, the axis of the keeper being substantially parallel to the pivotal axes of the hinges of the door.

The pin 331 is mounted in a bearing 332 on a bracket 339 extending from the plate 333, secured 25 to the jamb by screws 334.

I have in Figs. 13, 14 and 15 exemplified the keeper and latch lever at the inside of the door, the keeper being mounted on the door jamb and the latch lever and its casing on the door. Similar parts in these figures are designated by similar numerals raised to the series 400. In this instance, the keeper 431 is rotatably adjustable in a bearing 432 on a plate 433 secured to the sealing strip 408 and to the jamb in a recess 490.

An outer handle 487 is provided on an escutcheon plate 488, secured to the outer face of the door, to be grasped by the operator at the outside of the door for opening or for closing the door. The latch operates automatically in response to the opening or closing movement for latching or unlatching the door.

The inner face of the door may be provided with a handle in each of the exemplifications shown and described for pulling the door into closing 45 position.

Having thus fully described my invention, what I claim as new and desire to secure by Letters Patent is:

In a latch, the combination of a casing, a lever having a pivot in said casing and having a latching end at one side of said pivot, a rod whose one end has articulating connection with said lever at the opposite side of said pivot and whose other end has articulating connection with said casing, 55 said rod having an enlargement at each of its ends, said enlargement at said first-named end being threaded, the pivotal axis of said first-named articulating connection movable by opposite pivotal movements of said lever to opposite 60 sides of a right line between the pivotal axis of said second-named articulating connection and the pivotal axis of said lever, a nut threaded to said threaded enlargement, a helical spring about said rod between said nut and a stationary part of said casing with the respective ends of said helical spring about said enlargements for centering both ends of said spring about said rod and said parts being so related that adjustment of said nut on said threaded enlargement adjusts the 70 tension of said spring, and said second-named enlargement movable axially in said spring upon pivotal movement of said lever.

OSCAR C. SCHMIDT.
